UNITED STATES PATENT OFFICE

162,172

ASH TRAY COVER

Walter L. Jones, South Wales, N. Y., assignor to McDonald Products Corporation, Buffalo, N. Y., a corporation of New York

Application March 31, 1949, Serial No. 1,727

Term of patent 14 years

(Cl. D85—2)

To all whom it may concern:

Be it known that Walter L. Jones, citizen of the United States, residing at South Wales, in the county of Erie and State of New York, has invented a new, original, and ornamental Design for an Ash Tray Cover, of which the following is a specification, reference being made to the accompanying drawing, forming a part thereof.

Fig. 1 is a perspective view of an ash tray cover showing the new design; and

Fig. 2 is a top plan view thereof.

The invention claimed is:

The ornamental design for an ash tray cover, as shown.

WALTER L. JONES.
